S. A. NONSUCH,
APPLIANCE FOR FINISHING CRANK PINS.
APPLICATION FILED DEC. 3, 1920.

1,412,887.

Patented Apr. 18, 1922.

UNITED STATES PATENT OFFICE.

SCIOTA A. NONSUCH, OF PHILADELPHIA, PENNSYLVANIA.

APPLIANCE FOR FINISHING CRANK PINS.

1,412,887.

Specification of Letters Patent. Patented Apr. 18, 1922.

Application filed December 3, 1920. Serial No. 427,939.

To all whom it may concern:

Be it known that I, SCIOTA ALBERT NONSUCH, a citizen of the United States, residing in the city of Philadelphia, in the county of Philadelphia and State of Pennsylvania, have invented certain new and useful Improvements in Appliances for Finishing Crank-Pins, whereof the following is a specification, reference being had to the accompanying drawings.

My invention relates to appliances for finishing crank-pins, and more especially for refinishing the crank-pins of automobile engines after they have been worn out of shape or their surfaces have been scratched and damaged in use. With my appliance, the crank-pins of such an engine can be accurately and expeditiously refinished without removing the crank shaft from the engine or otherwise dismantling it,—excepting only to the extent of disconnecting the connecting rods from the crank-pins to be refinished. My appliance is simple and rugged in construction and economical to manufacture, besides being convenient, durable, and accurate in use.

Various other advantages of my invention will appear from the description hereinafter of the best embodiment at present known to me, while its scope and essentials in its various phases will be indicated in my claims.

In the drawings, Fig. I is a side elevation of my appliance, showing it mounted for operation on a crank-pin,—which appears in cross-section.

Fig. II is an edge elevation from the right of Fig. I.

Fig. III shows a cross-section at a plane corresponding to the line III—III in Fig. I.

Fig. IV is an enlarged view illustrating the form and action of the cutting part of the tool employed in the appliance.

Fig. V is a plan view of said cutting part.

Fig. VI is a side elevation illustrating the operation of the appliance on a crank-pin in an engine.

Figs. VII and VIII are enlarged fragmentary views, partly in section, illustrating the operation of the appliance on different forms of crank-pins.

The form of appliance here illustrated (see Figs. I and II) has a frame structure 1 comprising a massive, rigid yoke 2 open at one side, a massive elongated handle 3 rigid with the yoke 2 extending from one side thereof, and a strong, rigid bridge member 4

that can be rigidly secured across the opening of the yoke, so as to form a solid tensile connection thereacross when the appliance is in use, but is removable from across said opening to permit the introduction of a crank-pin 9 within the yoke. The yoke 2 and the handle 3 are formed of one integral piece of metal, and in outline merge gently into one another. The bridge member 4 is in the form of a U-shaped stirrup of heavy sheet metal; its ends are pivoted to the front lower corner of the yoke 2 by a pin 5 extending therethrough, and its center carries a set screw 6 that is threaded therethrough and engages in a socket 7 on the front upper corner of the yoke. When the screw 6 is tightened up hard, the member 4 is made firm and rigid across the mouth of the yoke 2. The frame structure 1 carries the surfacing tool 10 for refinishing the cylindrical bearing surface of the crank-pin 9, and also bearing means for maintaining the frame and the tool in the proper relation to the crank-pin 9 for securing the desired action of the tool on the latter.

As shown in Figs. I and II, the bearing means comprises a bearing block 11 mounted on the yoke 2 directly opposite the tool 10; a bearing block 12 at the following side of the tool, also mounted on said yoke; and another bearing block 13 at the leading side of the tool, mounted on the bridge member 4.

The bearing surfaces of these bearing blocks or members 11, 12, and 13 are curved in substantial conformity to the circular curvature of the crank-pin surfaces that they engage. The bearing surface of the block 11 opposite the tool 10 extends over a very considerable arc or angle (some 150°) and is "eased", so to speak, by curvature to a radius sufficiently greater than that of the crank-pin surface which it engages to make its ends about one-thousandth of an inch from said surface when its middle is in contact therewith, so as to permit slight variation of the region or line of greatest contact pressure against the cylindrical or curved surface of the crank-pin 9. (In Fig. I, of course, this difference of curvature between crank-pin and bearing block 11 is exaggerated in order to make it perceptible.) At its rear, the bearing block 11 has a flat face (perpendicular to the center line of the tool handle 3) that rests against a corresponding flat surface on that side of the yoke 2 and is flanked by inclined sur-

100

105

110

faces that engage correspondingly inclined surfaces on the yoke; it is firmly held or clamped in place by a headed screw 16 that extends through the yoke and takes into a threaded hole in the block.

- The bearing 12 at the following side of the tool 10 has its bearing surface curved to the radius of the circular crank-pin surface that it engages, and its rear face is shaped 10 to engage the corresponding inside surfaces of the yoke 2, against which it should preferably rest. A set screw 17 threaded through the yoke 2 adjacent the handle 3 at about a 45° angle with the center line of 15 said handle engages the rear face of the bearing block 12 (which face is normal to the axis of the set screw) and serves as a means of independently adjusting the bearing 12 with reference to the yoke 2, the 20 bearing 11, and the tool 10. The leading side of the bearing block 12 is parallel with the center line of the handle 3 and engages the following side of the tool 10; by this means, displacement of the block 12 circumferentially of the crank-pin 9 being operated on is prevented. The bearing 12 prevents undue entry of the pin 9 toward the bottom or rear of the yoke 2, and also limits the depth of the bite and cut of the tool 10. 25
- The other bearing 13 at the leading side of the tool 10 has its bearing surface curved to the radius of the cylindrical pin surface that it engages, and is mounted on the bridge member 4 in a position substantially 30 at a right angle from the tool, so as to bear against the pin 9 along an arc whose middle point falls a little below (toward the tool 10 from) a plane through the center of the pin perpendicular to the center line 35 of the tool handle. As shown, the rear face of the block 13 is curved, near its edges, in conformity with the arc-shaped rear inner edges of the sides of the member 4, so that said block shall seat and ride on said yoke. 40
- The curvature of the yoke edges is to a 45 radius greater than that of the pin 9 and about a center a little above the plane through the latter perpendicular to the center line of the handle 3. Thus the bearing 50 13 has a wedge form in reference to its front and rear curved surfaces; and when it is forced upward circumferentially of the pin 9, its bearing surface is thrown and tilted toward the bottom of the yoke 2 55 a little, so as to press harder against the pin 9. This circumferential adjustment of the block 13 is effected, by means of a set screw 21 threaded through a lug 22 projecting from the back of said block between the sides of the member 4 and bearing in a 60 socket or depression 23 in the lower forward corner of the yoke 2. The bearing 13 contacts with the bearings 11 and 12, therefore, in controlling the position or centering of 65 the frame 1 on the pin 9 by a wedging

action, and tends to insure more even, uniform, smooth action by the tool 10.

The tool 10, it will be seen, comprises a generally rectangular, oblong block of metal mounted in a close, snug socket 25 in the 70 portion of the yoke 2 that merges with the handle 3. In order that the tool 10 and the bearing 11 may be adjusted relatively to one another, the tool is arranged to slide in the socket 25 as a slideway, and is screwed 75 fast on the end of a rod 26 lying in a curved bottomed groove in the handle 3 and in threaded engagement with a cylindrical nut member 27 mounted in a recess near the end of the handle. (See Figs. I and III). 80 The rod 26 and the tool block 10 are retained in place by a filler member 28 in the groove that is itself mounted on the inner side of a cover plate 29 screwed to the handle 3 over the groove. The nut member 85 27 has round holes 31 for receiving the end of a rod for turning the nut to adjust the tool.

The active portion of the tool 10 consists of a suitably hardened and tempered metal 90 strip 33 (see Figs. I and IV) dovetailed in an undercut groove across the outer end of the tool block. This strip 33 is so proportioned and arranged that its leading corner 95 34 is about in the plane of the center line L of the handle 3,—which center line L, as shown, also extends through the center of the pin 9 when the bearings 12 and 13 are suitably adjusted, and thus constitutes the center line of the whole appliance in a functional sense. While the top surface 35 of the piece 33 is preferably very nearly perpendicular to the center line L just mentioned, it need not be exactly so, but may be inclined back from the leading edge, toward 100 the remote side of a plane tangent to the pin at that point, at an angle of, say, $\frac{1}{2}$ of one degree: this is shown with much exaggeration in Fig. IV. The forward surface of the piece 33 immediately subjacent to its 105 leading corner may be substantially parallel to the center line aforesaid, or slightly inclined forward therefrom. While the sharp leading corner 34 of the piece 33 may act as cutter or scraper if its top surface 35 be 110 plain, I prefer to groove this top surface 35 (like a file) at an inclination, as shown in Fig. V, so as to secure a file action.

In Fig. VI, I have illustrated diagrammatically the employment of my appliance in 120 refinishing a crank-pin of an automobile internal combustion engine. As shown, the connecting rod 38 is disconnected from the crank-pin to be refinished, and the corresponding piston 41 is blocked up in the upper 125 end of its cylinder, so as to keep the connecting rod up out of the way as much as possible. My device having been applied to the crank-pin as shown, the crank shaft 42 is revolved once or twice (as by the start- 130

ing crank), the handle 3 being allowed to slide against the crank case, which prevents it from turning. The device 1 being so applied and the crank shaft 42 so rotated as to 5 make the edge or corner 34 of the piece 33 the leading one, the crank-pin surface will be very quickly refinished and trued. (Note the arrows in Fig. IV, indicating the direction of rotation of the crank-pin 9 with reference to the frame 1).

I have so far spoken as if the bearings 11, 12, and 13 engaged the very bearing surface of the crank-pin that is being refinished. From Figs. VII and VIII, it will be seen 15 that this is not the case, but that these bearings 11, 12, and 13 are of sufficient width axially to seat and engage on the crank-pin beyond (at the sides of) the bearing surface portion thereof that is to be finished or re- 20 finished, and that the tool edge is of such width (and the corner 34 of such length) that the tool shall engage and act only on the portion of the pin intermediate the portions effectively engaged by the bearings 25 11, 12, and 13.

As here shown, the bearings 11, 12, and 13 engage and center the frame 1 on zones of the crank-pin 9 (at either side of the originally round and normally active wearing 30 portion of the crank-pin) that are usually trued and even finished when the crank-pin is turned up and finished, but are normally outside the zone of wearing contact with the connecting rod bearings and so normally re- 35 main inactive and unworn in use. In Fig. VII, where the crank-pin shown has square unfileted flanges 45 at its ends, these zones comprise simply narrow marginal end portions 46 of the cylindrical part of the crank- 40 pin; in Fig. VIII, where the crank-pin has fillets 47 at its ends, said zones comprise the rounded fillet surfaces. As shown in Fig. VII, the bearing surfaces of the bearing blocks 11, 12 and 13 are on square cor- 45 nered narrow ridges 48 formed by broad, shallow grooves in the bearing blocks, of slightly less width than the acting part 33 of the tool; while in Fig. VIII, the bearing surfaces of the bearing blocks are formed by 50 the beads of round cornered ridges 49. The ridges 48 and 49 are shown as of greater width than the crank-pin zones 46 and 47 which they are intended to engage actively and center on; but this does not interfere 55 with the proper action of the appliance. In a word, therefore, the tool 10 engages and refinishes only the normally active central wearing portion of the pin, intermediate the inactive zones 46, 46 or 47, 47. It will be 60 observed that the bearing blocks 11, 12, and 13 are of such thickness as to fit closely between the finished flat surfaces of the shoulders or flanges 45 with only a clearance of one-thousandth of an inch, for example, 65 so that the appliance is guided and kept in

just the right position, without end play or wabbling or twisting sidewise. This, of course, helps in insuring a true cylindrical surface for the refinished crank-pin, regardless of irregular wear or other deformation 70 before refinishing.

Having thus described my invention, I claim:

1. A finishing appliance for the round wearing surface of a crank-pin comprising 75 a frame with bearings adapted to engage the pin only at the sides of the portion thereof to be finished, and a surfacing tool on said frame adapted to engage only the portion of said pin intermediate the afore- 80 said frame bearings.

2. A finishing appliance for the cylindrical wearing surface of a crank-pin comprising a frame with bearings adapted to engage and center the frame on trued but normally inactive zones at either side of the round normally active wearing portion of the crank pin, and a surfacing tool on said frame adapted to engage and refinish only said normally active wearing portion of said 90 pin intermediate said inactive zones.

3. A crank-pin finishing appliance comprising a yoke adapted to embrace the pin on three sides and open on the fourth side to permit it to be placed on the pin, and having a bearing for the pin and a surfacing tool opposite one another and adjustable with reference to one another; a bearing for said pin on said yoke at the following side 95 of the tool preventing undue entry of the pin into the yoke and limiting the depth of bite of the tool; and an independently adjustable bearing shiftable into a position in the opening of the yoke substantially at a right angle from the tool on the leading 100 side thereof.

4. A crank-pin finishing appliance comprising a frame with a bearing for the pin and a surfacing tool opposite one another and adjustable with reference to one another, a bearing for said pin on said frame at the following side of the tool independently and positively adjustable with reference to said frame to control the action 110 of the tool, and another bearing for said pin mounted on said frame at the leading side of the tool and adjustable circumferentially 115 of the pin to control the position of the frame thereon by a wedging action.

5. In a crank-pin finishing tool, the combination of a rigid yoke adapted to embrace the pin on three sides and open on the fourth side to permit it to be placed on the pin; an elongated handle rigid with said yoke extending from one side thereof, said yoke having therein a socket for a surfacing tool adjacent the handle and a bearing for the pin opposite said socket; a surfacing tool adjustable in said socket with its leading edge toward the open side of the yoke; a 120

bearing for said pin on said yoke at the following side of said tool preventing undue entry of the pin into the yoke and limiting the depth of bite of the tool, said latter bearing being independently and positively adjustable with reference to said yoke; and a tension member secured across the opening of said yoke.

6. A crank-pin finishing tool comprising
10 a rigid yoke adapted to embrace the pin on three sides and open on the fourth side to permit it to be placed on the pin; an elongated handle rigid with said yoke extending from one side thereof, said yoke having
15 therein a socket for a surfacing tool adjacent the handle and a bearing for the pin opposite said socket; a surfacing tool adjustable in said socket with its leading edge

toward the open side of the yoke; a bearing for said pin on said yoke at the following 20 side of said tool preventing undue entry of the pin into the yoke and limiting the depth of bite of the tool, said latter bearing being independently and positively adjustable with reference to said yoke; a bridge member rigidly secured across the opening of 25 said yoke; and a bearing adjustable on said bridge member at the leading side of said tool.

In testimony whereof, I have hereunto signed my name at Philadelphia, Pennsylvania, this 29th day of November, 1920.

SCIOTA A. NONSUCH.
